Primary Examiner—Melanie H Tung*Assistant Examiner*—Lavone D Tabor(74) *Attorney, Agent, or Firm*—AMy M. Fernandez(57) **CLAIM**

The ornamental design of a set of bristles for a toothbrush, as shown and described.

DESCRIPTION

FIG. 1 is a perspective front view of a set of bristles for a toothbrush showing my new design;

FIG. 2 is an enlarged front view thereof;

FIG. 3 is an enlarged right side view thereof; and,

FIG. 4 is an enlarged left side view thereof.

The broken line showing of the remainder of the toothbrush is for illustrative purposes only and forms no part of the claimed design.
